LIQUID DISPENSING DEVICE

Joseph M. Majewski, Jr., Kansas City, Mo.

Application February 24, 1941, Serial No. 380,283

2 Claims. (Cl. 221—67)

My invention relates to a liquid dispensing device and more particularly to a liquid dispenser adapted to be used in connection with insulated containers for liquids.

Picnic jugs and other similar containers such as Dewar flasks sold under the trade name of "Thermos bottles" are adapted to contain hot or cold liquids and keep them at elevated or low temperatures for considerable periods of time. The dispensing of fluids from these jugs has been accompanied by the necessity of removing the cap either to pour liquids out or in the case of those containers provided with spigots to permit the venting of the vessel.

Air lines frequently employ insulated jugs for the serving of soups, coffee, iced tea, and the like. In airplanes, the motion of the plane makes it exceedingly difficult to dispense fluids from insulated jugs in the usual manner. When the jug is opened, either to remove liquid therefrom or to vent the same, its contents are often spilled.

One object of my invention is to provide a simple and expeditious means of dispensing fluids from heat insulated jugs and similar containers.

Another object of my invention is to provide a dispensing means which will seal the vessel when liquids are not being withdrawn therefrom.

Other and further objects of my invention will appear from the following description.

In the accompanying drawing which forms part of the instant specification and is to be read in conjunction therewith and in which like reference numerals are used to indicate like parts in the various views;

Figure 1 is an elevation of a heat insulated jug, equipped with one embodiment of my invention.

Figure 2 is an enlarged sectional view, with parts broken away, taken on the line 2—2 of Figure 1, with the parts in jug-sealing position.

Figure 3 is a fragmentary side elevation, with parts in section, on an enlarged scale, taken 180° from the section shown in Figure 2, with the parts in fluid dispensing position.

Referring now to the drawing, the container 1 may be of any suitable type such as a ceramic or glass vessel 2, which is provided with a heat insulating blanket 3, protected by a sheet metal casing 4. A cap 5, provided with a sealing stopper 6 of any suitable construction, is adapted to be screwed onto the neck of the jug by means of screw threads 7. Secured to the cap in any suitable manner is an assembly which embodies

my invention. It comprises a casting 8, provided with a flange 9 which may be riveted, brazed, welded or otherwise secured to the cap. The casting 8 is formed with a duct 10, ending in a spigot 11 through which the liquid within the jug is adapted to flow in removing it from the jug. A vertical bore 12 is likewise formed in the casting. A tube 13 passes into the bore 12 and extends upwardly into the jug, as can readily be seen by reference to Figure 2. Secured to the tube 13 is a valve holding member 14 in which a valve 15 is positioned. The casting 8 is formed with an annular raised portion 16 which forms a valve seat preventing the flow of liquid from the jug. The tube 13 may be made of any suitable material such as stainless steel or, if desired, a suitable plastic material. Housed within the tube 13 I provide a rod 17, to the lower end of which is secured a plug 18 by means of a screw 19, threaded in the lower end of the rod 17. The upper end of rod 17 carries a valve holding member 19', in which a valve 20 is positioned. The upper periphery of the tube 13 acts as a valve seat, against which the valve 20 seals. The valve assembly is secured to the upper end of rod 17 by means of a screw 21. A spring 22 within the bore 12, acting against the plug 18, urges the rod 17 downwardly, thus seating the valve 20 on the upper end of tube 13. This forces tube 13 downwardly and seats valve 15 against its seat 16. The lower end of tube 13 within the bore 12 is provided with a plurality of openings 23. The plug 18 is formed with a pair of lugs 24, extending outwardly through slots 25 formed in the sides of the bore 12. A bifurcated lever 26 straddles the spigot 11 and is pivoted to the casting 8 by pivot pin 27. An operating handle 28 is secured to the bifurcated lever 26 by means of a screw 29. Arms 30 of the lever 26 engage the lugs 24 in the plug 18.

In operation, when it is desired to dispense liquid from the jug 1, the lever 26 is operated, rotating it about its pivot pin 27. The arms 30, in engagement with the lugs 24, raise the plug 18, thus raising the rod 17. It will be noted that the lower end of tube 13 is spaced away from the plug 18 so that there is an upward movement of the rod with respect to the tube 13, against the action of the spring 22. This first movement raises the valve 20 from its seat and vents the interior of the jug above the liquid level therein. Continued motion of the plug 18 upwardly under the influence of the lever 26 against the action of the spring 22 then moves the tube 13 upwardly, together with the rod 17. It will be ob-

served that the rod 17 maintains its relative position with tube 13; that is, that the air vent at the top opens. The upward movement of the tube 13 lifts the valve 15 from its seat and permits liquid to flow out of the spigot 11. As the liquid flows out of the spigot 11, air from the duct 18 through the slots 25 in the duct enters the openings 23 in the tube 13 and flows upwardly through the tube to the space above the liquid in the jug. Some air will also pass upwardly through the space between the tube 13 and the casting 8. This air flows into the eduction liquid by induction of its flow past the annular space between the casting 8 and the tube 13. The flow of air into the eduction liquid prevents leakage of liquid into the bore 12. When the lever 26 is released, the spring 22 will first permit the valve 15 to cease shutting off the liquid flow, then seats the valve 20, sealing off the vent tube. The jug is thus automatically sealed and no liquid will escape, irrespective of the motion of the jug.

It will be seen that I have accomplished the objects of my invention. I have provided a simple and expeditious liquid dispensing device 25 for heat insulated jugs and the like, which automatically vents the jug when liquid is being withdrawn therefrom and in which the vent is sealed when liquid is not being withdrawn.

It will be understood that certain features and sub-combinations are of utility and may be employed without reference to other features and sub-combinations. This is contemplated by and is within the scope of my claims. It is further obvious that various changes may be made in details within the scope of my claims without departing from the spirit of my invention. It is, therefore, to be understood that my invention is

not to be limited to the specific details shown and described.

Having thus described my invention, I claim:

1. In combination with a container adapted to contain liquid, a spigot, a liquid valve for controlling the flow of liquid from said container through said spigot, a vertical tube extending upwardly into said container, means for mounting said liquid valve on said tube, a vent valve sealing the upper end of said tube, a rod positioned within said tube, means for securing said vent valve to the upper end of said rod, means carried by the lower end of said rod normally out of engagement with the lower end of said tube, and means for moving said rod upwardly, the construction being such that the initial movement of said rod will open said vent and continued movement of said rod will move said tube upwardly to open said liquid valve.
2. In combination with a container adapted to contain liquid, said container formed with an opening, a liquid closure valve for said opening, a spigot having communication with the interior of said container through said opening and controlled by said liquid closure valve, a tube extending upwardly through said opening into said container, said liquid closure valve mounted about said tube, a vent valve sealing the upper end of said tube, an elongated member extending through said tube and secured to said vent valve, spring means for urging said elongated member downwardly to seat said vent valve upon said tube and to urge said tube downwardly whereby to seat said liquid closure valve, and means for lifting said vent valve and liquid closure valve in succession.

JOSEPH M. MAJEWSKI, JR.
